PUSH-OFF ATTACHMENT FOR LIFT TRUCKS
Stuart W. Sinclair, Houston, Tex., assignor to Anderson,
Clayton & Co., Houston, Tex., a corporation of
Delaware

Filed Jan. 6, 1964, Ser. No. 335,884
4 Claims. (Cl. 214—514)

The present invention relates to push-off attachments for lift trucks, and more specifically to a push-off attachment for use in removing a load from the tines of a fork lift truck, and improvements in the construction thereof.

In the past, push-off attachments have been either of the lazy tongs arrangement, a parallelogram arrangement or of the horizontal slide arrangement. Examples of these prior structures are found in the U.S. Patent Nos. 2,993,610; 2,619,241; 2,672,269; and 2,590,355. With the first two types, the sagging of the pusher plate, particularly when it is extended, has been somewhat of a problem. In the last type, the bulk and length of the device have presented maneuverability problems. It is an object of the present invention to overcome the foregoing disadvantages of the prior art structures in a manner not previously contemplated.

Another object of the present invention is to provide a push-off attachment which is quite rigid, even when fully extended, is relatively simple, and which folds into a small unit adjacent to the lift truck body when retracted.

Yet another object of the present invention is to provide a push-off attachment which does not substantially increase the overhang in the front of the lift truck when retracted.

Yet another object of the present invention is to provide a push-off attachment which includes pivoted yokes and pivoted equalizers set at 90° from the yokes, so as to prevent sagging of the pusher plate when fully extended, and at the same time allows the attachment to be folded into a very small unit when the pusher plate is retracted.

A still further object of the present invention is to provide a push-off attachment which includes hydraulic motor means for actuation thereof, which motor means may be placed in such a position that it does not substantially increase the overall width of the attachment when the pusher plate is fully retracted. A particular advantage of this arrangement is that it allows the pusher plate to be shifted horizontally by means of other typical lift truck attachments, thus increasing the overall versatility of the unit.

A further object of the present invention is to provide a push-off attachment wherein the hydraulic motor means extends and retracts the pusher plate in exact proportion to the volume of fluid in the motor, so that movement of the pusher plate is uniform.

Other further objects, features and advantages will be apparent from the following description of presently preferred embodiments of the invention, given for the purpose of disclosure, taken in conjunction with the accompanying drawings, where like character references designate like parts throughout the several views, and where:

FIGURE 1 is a side view of a lift truck which includes the present invention thereon in the act of discharging a load from the fork tines.

FIGURE 2 is an enlarged partial side view, partially in section, showing in detail the attachment of FIGURE 1.

FIGURE 3 is a top view, partially in section, of the attachment of FIGURE 2.

FIGURE 4 is a front view, partially in section, of the attachment of FIGURE 2.

2

FIGURE 5 is a side view, similar to FIGURE 2, of modification of the present attachment, and

FIGURE 6 is a side view showing the attachment of FIGURE 5 when retracted.

5 The invention generally comprises a frame, a pair of hinged or pivoted yokes, a pair of hinged or pivoted equalizers set at 90° from the yokes, and means for extending and retracting a pusher plate relative to the frame.

Referring now to the drawings, and particularly to FIGURE 1, the reference numeral 10 generally refers to a conventional fork lift truck which includes a mast 12 to which are attached vertically movable fork tines 14 by means of the bracket 16. In such trucks 10, means 18 are conventionally provided for raising and lowering the tines 14. Attached also to the bracket 16 is the push-off attachment 20 of the present invention, which will be described in greater detail hereinafter. Generally, however, the push-off attachment 20 includes the vertical pusher plate 22 which may be horizontally traversed relative to the mast 12, so that a load 24 carried on the tines 14 may be pushed off or pulled on the tines by the lift truck 10. Although not shown, the pusher plate 22 may have various pallet grippers mounted thereon to expand the use of the lift truck 10, in a manner similar to those illustrated in the patents previously mentioned. As such pallet grippers form no part of the present invention, they are not illustrated.

Referring now to FIGURE 2, the push-off attachment 20 will be explained in greater detail. Attached to the bracket 16, in any suitable manner such as by welding, is a frame 26. Pivotably attached to the frame 26 is a rear yoke 28, and pivotably attached to the rear yoke 28 is the front yoke 30. In turn, the front yoke 30 is pivotably attached to the pusher plate 22. The pivotable attachments in each instance are all parallel, here shown as horizontal and include the hinges 32, 34 and 36 respectively.

With reference now to FIGURES 3 and 4, it will be noted that both the rear and front yokes 28 and 30 generally resemble large letter C's which are joined back to back by means of a group of three hinges 34, while the extended ends of the yoke are joined respectively to the frame 26 and plate 22 by a pair of hinges 32 and 36. Although three pairs of hinges 34 are shown, this is merely a matter of convenience and a greater or smaller number may be utilized. It is to be particularly noted that the hinges 32 are parallel to the hinges 34 and that the hinges 34 are parallel to the hinges 36, consequently the plate 22 will be parallel to the frame 26 at all times.

Referring again to FIGURE 2, pivotably attached to the frame 26 is a rear equalizer 38, and pivotably attached to the rear equalizer 38 and the pusher plate 22 is a front equalizer 40. The pivotable attachments are all parallel and are here shown as the vertical hinges 42, 44 and 46 respectively.

55 As can be seen by comparing FIGURES 2, 3, and 4, the hinges 42, 44, and 46 are all parallel, consequently the pusher plate 22 is prevented from dropping or sagging with reference to the frame 26. Furthermore, since the equalizers 38 and 40 are mounted at right angles to the yokes 28 and 30, it is apparent that the hinges 32 and 42 define a plane which is parallel to the plane defined by the hinges 36 and 46. A further plane is defined by the hinges 34 and 44, which is likewise parallel to the previously mentioned planes. Consequently, the pusher plate 22 is held vertically and parallel to the mast 12 no matter what its extension from the frame 26.

Because the front and rear yokes 28 and 30 are shaped, it is possible for the pusher plate 22 to be greatly retracted and for the folded equalizers 38 and 40 to be within the open ends of the yokes so that the entire attachment 22 forms a very compact unit. Thus, as seen in FIGURE 3, the length of either equalizer 38 or 40

ess than the distance between the ends of either yoke or 30.

With reference again to FIGURE 2, the reference numeral 48 generally refers to the means for traversing or acting and extending the pusher plate 22, and is here shown as a hydraulic motor. The hydraulic motor generally consists of a cylinder 50 having a piston 52 slidably mounted therein. The cylinder 50 is attached to the rear yoke 28 by means of a bracket 54 and pivotal connection 56 on the plate 70. The piston 52 is attached to the front yoke 30 by the connecting rod 58 and pivotal connection 60 on the lug 72. Fluid pressure supply means 62 and 64 are connected to the cylinder 50 so that hydraulic fluid may enter therethrough to reciprocate the piston 52 within the cylinder 50. As can be seen in FIGURE 3, a pair of identical means 48 are provided, although it would be well within the skill in the art to delete or add additional units.

The pusher plate 22 generally comprises a flat plate whose outer edges 66 are turned back, thereby forming a generally rectangular pan. When the pusher plate 22 is fully retracted, the rolled back edges 66 cover the operating mechanism as an additional safety advantage. With reference particularly to FIGURE 4, it will be noted that there are several cut outs 68 in the front of the plate in order that the hinges 34 and 36 may extend therethrough. In this manner, when the plate 22 is fully retracted, the over-all width of attachment 20 is reduced. With reference again to FIGURE 2, the double-headed arrow immediately above the plate 22 shows the directional movement of the plate relative to the frame 26. When fully retracted, the plate 22 is shown in dotted lines 22'. In a similar manner, the double-headed arrow above the means 48 shows the relative movement of the arms when retracting and extending the pusher plate 22. The retracted position of the means 48 is shown in dotted lines as 48'.

It is to be noted that the particular disposition of the means 48 is such that similar triangles are produced. That is to say, that the triangle formed with its apex as the hinge 34 and its two legs terminating at the hinges 32 and 36 is similar to the triangle with its apex 34 and two legs terminating at the pivotal connections 56 and 60. Consequently, the reaction of the means 48 on a smaller similar triangle produces a linear proportional movement in the yokes 28 and 30, and therefore the rear plate 20. In this manner, advantageously, the present invention provides a push-off attachment wherein the movement of the pusher plate 20 is directly proportional to the volume of fluid introduced into the cylinder so that the operator need not make adjustments to attain a uniform traverse speed.

In use, the fork lift truck 10 is maneuvered until the tines 14 may be inserted beneath the load 24. Thereupon, the pusher plate 22 may be retracted against the mast 12 by inducing hydraulic fluid through the fluid pressure means 64 to activate the piston 52, which in turn draws the connecting rod 58 into the cylinder 50, thus swinging the pivotal connections 56 and 60 together. This in turn draws the hinge 36 towards the hinge 32, thereby retracting the pusher plate 22 against the frame 26 to the position shown as 22' in FIGURE 2. At this stage, or simultaneously with the previously described action, the truck may be moved forward so that the tines under the load 24 thereby allowing the truck 10 to lift the load and maneuver it to any desired position.

To remove the load 24 from the tines 14, fluid is introduced through the fluid pressure means 62, thereby pushing the piston 52 and the connecting rod 58 so that the pivotal connections 56 and 60 are moved apart. This in turn causes the hinge 36 to move away from the hinge 32, thereby extending the pusher plate 22. At the same time, the combination of the yokes 28 and 30 and the stabilizers 38 and 40 prevent the pusher plate 22 from

sagging and maintain it in a position which is at all times parallel to the frame 26.

With reference now to FIGURES 5 and 6, a modification of the device shown in FIGURE 2 is illustrated, wherein the majority of the various elements are substantially identical to those previously described, and hence have been given identical numbers. In this modification, it will be noted that the means 48 is aligned substantially vertically instead of horizontally as in FIGURE 2. The particularly advantageous result obtained thereby is seen in FIGURE 6, wherein it will be noted that the means 48 remains substantially vertical and does not extend any great distance behind the frame 26 as does the comparable means 48' in FIGURE 2.

It should be further noted when comparing FIGURES 5 and 2 that the cylinder 50 is attached to the front yoke 30 and connecting rod 58 is connected to the rear yoke 28 in FIGURE 5, while the parts are reversed in FIGURE 2. In any event, it is to be noted that the same similar triangles as shown in FIGURE 2 exist in FIGURE 5 such that the triangle formed by the hinges 74, 76, and 34 is similar to the triangle formed by the hinges 32, 36, and 34. Consequently, the same linear motion produced by the device of FIGURE 2 is produced by the device of FIGURE 5. Said another way, the similar triangles of FIGURE 5 have merely been rotated, but still remain similar and in addition to providing the same function as before, advantageously allow the cylinder 50 to be mounted more compactly.

As before, the means 48 for traversing or retracting the pusher plate 22 is here shown as a hydraulic motor. The hydraulic motor generally consists of a cylinder 50 having a piston 52 slidably mounted therein. The cylinder 50 is attached to the rear yoke 28 by means of a bracket 78 and pivotal connections 76 on the lug 80 which forms a part of the yoke 30. The piston 52 is attached to the rear yoke 28 by the connecting rod 58 and pivotal connection 74 on the plate 82 which forms a part of the rear yoke 28. Fluid pressure supply means 84 and 86 are connected to the cylinder 50 so that hydraulic fluid may enter therethrough to reciprocate the piston 52 within the cylinder 50. Just as was shown in FIGURE 3, a pair of identical means 48 may be provided, although it would be well within the skill in the art to delete or add additional units.

Upon the introduction of hydraulic fluid to the cylinder 50, the movement of the hinge 34 and the pusher plate 22 respectively are shown relative to the frame 26 by the double-headed arrows above these items. Thus, upon the introduction of hydraulic fluid through the supply means 84, the piston 52 is activated and the pivotal connection 74 is pushed further from the pivotal connection 76, thus resulting in traversing the pusher plate 22 by extending it from the frame 26 by means of the reaction on the rear and front yokes 28 and 30. To retract the pusher plate 22, hydraulic fluid is introduced through the supply means 86, thus pushing the piston 52 within the cylinder 50 and drawing the pivotal connections 74 and 76 together, which in turn react upon the rear and front yokes 28 and 30. The position of this modification when fully retracted is shown in FIGURE 6. The use of the traversing of the pusher plate 22 of the modification shown in FIGURES 5 and 6 is identical to that described hereinabove with reference to FIGURES 1-4.

Thus, advantageously, the present invention has provided a push-off attachment which is quite rigid, even when fully extended, and which folds into a small unit adjacent to the lift truck body when retracted, as well as providing the other advantages previously mentioned.

The present invention, therefore, is well adapted to carry out the objects and attain the ends and advantages mentioned as well as others inherent therein. While presently preferred embodiments of the invention have been given for the purpose of disclosure, numerous changes in the details of construction, and the combination, shape,

size, arrangement of parts and uses may be resorted to without departing from the spirit and scope of the invention as hereinafter claimed.

What is claimed is:

1. The combination with a fork lift truck having a vertically movable bracket of a push-off attachment including:
  - a vertical frame attached to the bracket,
  - a first C-shaped yoke,
  - a second C-shaped yoke,
  - the yokes pivotally connected back to back,
  - a vertical pusher plate,
  - the ends of the first yoke horizontally pivotally connected to the frame,
  - the ends of the second yoke horizontally pivotally connected to the pusher plate,
  - a first equalizer,
  - a second equalizer,
  - the equalizers pivotally joined,
  - the first equalizer vertically pivotally connected to the frame,
  - the second equalizer vertically pivotally connected to the pusher plate,
  - a hydraulic motor including a cylinder and a piston,
  - the cylinder pivotally connected to one of the yokes,

the piston pivotally connected to the other of the yokes and fluid supply means connected to the hydraulic motor whereby the pusher plate may be traversed horizontally while maintained in parallel vertical alignment with the frame.

2. The invention of claim 1 wherein the length of each equalizer is less than the distance between the ends of each yoke.
3. The invention of claim 1 wherein the cylinder is mounted substantially horizontally.
4. The invention of claim 1 wherein the cylinder is mounted substantially vertically.
